UNITED STATES PATENT OFFICE.

THOMAS A. SOULTS, OF ROCHESTER, NEW YORK, ASSIGNOR TO STERLING RANGE AND FURNACE CORPORATION, OF ROCHESTER, NEW YORK, A CORPORATION OF NEW YORK.

SHELF ATTACHMENT FOR STOVES.

Application filed December 2, 1927. Serial No. 237,166.

This invention relates to stoves or ranges and more particularly to attachments for shelves or ovens generally provided on cooking stoves or ranges, one object being to provide a simple and economical form of rim or back strip for shelves or ovens on cooking stoves having effective means for securing the same in place on the stove. Another object is the provision of an attachment of this nature combined with simple means by which it may be secured to a stove in a neat and effective manner and at the same time substantially concealing from view all bolts or equivalent attaching means. A further object is the provision of a device of this character capable of being rigidly and permanently secured in place with a minimum number of bolts or other fastening devices.

To these and other ends the invention resides in certain improvements and combinations of parts, all as will be hereinafter more fully described, the novel features being pointed out in the claims at the end of the specification.

25 In the drawings:

Fig. 1 is a front elevation of a stove and shelf rim attachment embodying the present invention.

Fig. 2 is a rear elevation of the same.

30 Fig. 3 is an enlarged fragmentary side elevation of a shelf illustrating the manner of securing the rim or back strip supporting element to the shelf.

Fig. 4 is an enlarged fragmentary rear view 35 illustrating the manner of associating the back strip with its supporting element or bracket.

Fig. 5 is a detail front view of the left hand supporting bracket for the back strip.

40 Fig. 6 is a detail rear view of said bracket.

Fig. 7 is a sectional view taken on line 7—7 of Fig. 4.

Fig. 8 is a sectional view taken on line 8—8 of Fig. 4.

45 Fig. 9 is a sectional view taken on line 9—9 of Fig. 4 and drawn to a somewhat larger scale.

Similar reference numerals throughout the several views indicate the same parts.

50 The present embodiment of the invention provides an apparatus of the class described of simple and convenient form for use in connection with shelves or the like which is rugged, durable and capable of being produced

at moderate cost, being particularly advantageous for use in connection with stoves or ranges having a back shelf supported above the cooking surface, on which receptacles can be placed for the purpose of keeping their contents warm. To this end the invention, as disclosed, is embodied in an ordinary form of range having an upper supporting surface, in the form of a shelf or oven or combination of both, at the rear of which is supported an upstanding strip or flange for the purpose of preventing utensils placed thereon from rolling or sliding off the rear edge of the shelf. The strip or flange has at each end a bracket functioning both as a finish piece and as a support and is so interlocked with the shelf and back plate on the stove that all three elements may be held assembled by means of a single fastening device.

Referring more particularly to the drawings there is shown at 10 a stove such, for example, as a gas range, provided with an upstanding portion or back plate 11 extending thereacross and having a flat shelf section 12 disposed adjacent the top of the back plate 11 and extending forwardly therefrom. One end portion of the shelf section 12 is shown as extending outwardly somewhat farther than the other portion to form the top of an oven 13. An upstanding flange or strip 14 is disposed adjacent the juncture of the shelf 12 with the back plate and is held in place by supporting elements or brackets 15 at each end thereof.

For the purpose of stiffening the back plate and the shelf a frame or bracket 16 is suitably supported on the frame of the stove 10 and is secured to the edge of the back plate in any desired manner, as for example, by bolts 17. The edge of the shelf 12 is engaged with the upper forwardly extended part of the frame 16 in any desired manner, not shown.

While the shelf 12 can be made integral with the back plate 11, if desired, in the present instance it is formed of a separate sheet of metal and is secured to the upper edge 100 of the back plate by means of a downwardly bent portion 18 on the shelf suitably secured to the back plate 11 as by means of bolts 19, Fig. 4.

Brackets 15 are preferably located at the 105 rear corners of the shelf and are constructed in a manner so as to securely embrace the ends of the back strip 14 to hold it in fixed

position along the rear edge of the shelf. The brackets in the present instance are suitably formed of metal castings and are preferably symmetrically but reversely formed into rights and lefts, therefore a description of one of them will suffice for both. The bracket for the left hand end is illustrated in Figs. 3 to 9 inclusive. Referring particularly to Figs. 3, 5 and 9, the bracket has a downwardly projecting portion 20 affording a flat surface for engagement with the rear face of the back plate 11. An aperture 21 is formed in the portion 20 for the reception of a bolt 22, the head of which engages the frame member 16, 15 as shown in Fig. 9. A nut 22^a is secured on the end of the bolt 22 and bears against the outer surface of the downward projecting portion 20 and thus the frame 16, bracket 15 and back plate 11 are firmly held together. 20 A lock nut 22^b is preferably supplied on the bolt 22 for the purpose of holding the bolt 22 in place during construction to facilitate subsequent assembly of the members 14 and 15 with the stove in the event that it is desired to 25 pack and ship the stove without these members attached.

The bracket is formed also with an upwardly projecting corner member 23 which has a rounded front face 24 (see Fig. 8) for the 30 purpose of giving a rounded off and finished appearance thereto. This part of the bracket normally will be the only part which can be seen from the front of the stove when the parts are properly assembled. The front face 24 of 35 the bracket presents a shoulder 25 adjacent the downwardly projecting portion 20 which rests on the upper surface of shelf 12 and serves as a means for preventing angular movement of the bracket above the bolt 22, 40 thus holding the bracket rigidly upright.

The means for engaging the back strip 14 with the bracket may assume various forms. In the present embodiment the back strip is formed of a length of sheet metal having a 45 rounded upper edge 26 and a rearwardly projecting portion 27 at its lower edge. The vertical edge of the strip 14 is held from forward movement by means of its abutting engagement within a correspondingly shaped depression or socket 28 in the rear face of the corner member 23, as best seen in Fig. 6. The overhanging portion on the member 23 bears 50 on the rounded upper edge 26 and thus forms an abutment means for preventing upward movement of the strip. The rearwardly projecting portion 27 at the lower edge of the strip rests at its ends on the laterally projecting parts 29 of the brackets which serve 55 as abutments to prevent downward movement 60 of the strip. The rearwardly projecting portion 27 of the strip 14 is preferably cut away at 30, as shown in Figs. 4 and 8, for the purpose of facilitating assembly of the parts as will more clearly appear as the description 65 proceeds.

In order to prevent rearward movement of the strip 14 away from the bracket there is provided an upwardly extending abutment member or post 31 on the laterally projecting part 29 of the bracket and spaced from the 70 end thereof. This abutment member or post has a front face 32, which engages against the rear side of the strip 14. The upper end of the post is preferably rounded at 33 and fits beneath the rounded edge 26 at the top of the 75 strip 14 and serves as an additional abutment means for preventing downward movement of the strip 14.

The parts are preferably assembled by fitting the brackets 15 by an endwise sliding 80 movement onto the ends of the strip 14 until the ends engage against the abutments 34 at the inner edge of the depression or socket 28. It will be noted that the cut away portion 30 of the bent over edge 27 allows for free movement of the end of the strip 14 in place between the post 31 and the corner member 23, as seen in Fig. 8. With the strip and brackets in this relation they are placed in correct position at the rear of the shelf 12 and the bolts 22 are inserted and tightened to thus draw the lower portions 20 of the brackets securely against the rear face of the back plate 11. The back strip is thus quickly secured in an efficient and rigid manner at the rear edge of 95 the shelf.

It will be seen from the above description that the back strip 14 will be permanently and rigidly held by the brackets 15 against upward or downward movement, forward or 100 rearward movement, or endwise movement relatively to the shelf 12, this being accomplished merely by the abutment faces on the brackets, which, in turn, are held in place by a single bolt or like fastening means.

The invention thus affords a neat and attractive shelf for stoves having a back strip of a simple and convenient form secured thereto in a rugged, permanent and durable manner by effective bracket members. At 110 the same time the bracket members completely surround and cover the end edges of the back strip thereby giving a pleasing, rounded off and finished appearance to the stove and preventing any possible injury to the hands 115 by coming into contact with sharp corners or rough edges of the strip.

I claim as my invention:

1. The combination with a stove having an upstanding back plate with a shelf projecting therefrom, of an upwardly extending back strip disposed along the rear edge of said shelf, a bracket member having a base secured in fixed relation to said back plate and shelf adjacent the juncture thereof said base having an upstanding abutment portion adapted to contact the end of said strip and overlie a portion of the front face of said strip adjacent its lateral edge whereby forward and longitudinal movement of said strip 120

125

130

is prevented, and an additional abutment projecting upwardly from the base and independently of the first abutment adapted to prevent rearward and vertical movement of 5 said strip.

2. In combination with a stove having an upstanding back plate with a shelf projecting therefrom, of an upwardly extending back strip disposed along the rear edge of said 10 shelf, said strip having its upper edge bent rearwardly, bracket members on said back plate, said bracket members having abutment means overlying the front face of said strip adjacent its lateral edge and contacting the 15 upper face of said rearwardly bent edge, and additional abutment means on said bracket members spaced from the ends of the strip and contacting the rear face of said strip and engaging under said rearwardly bent edge.

20 3. The combination with a stove having an upstanding back plate with a shelf projecting therefrom, of an upwardly extending back strip disposed along the rear edge of said shelf, said strip having its lower edge bent 25 rearwardly and cut away adjacent the ends of said strip, bracket members on said back plate, comprising a downwardly projecting portion secured to said back plate, a laterally extending portion contacting beneath said 30 rearwardly bent lower edge, an upstanding abutment member on said laterally extending portion adapted to contact the rear face of said strip and an upstanding member at the outer side of said bracket having abutment 35 faces thereon adapted to contact the end and upper edges and front face of said strip.

4. In a bracket for back strips on stove shelves, a base portion adapted for attachment to the stove, an upstanding abutment member on said base having surfaces thereon 40 adapted to contact the front face and lateral and upper edges of said strip, and an additional abutment member extending upwardly from said base adapted to contact the 45 rear face of said strip, at a point spaced from its end, said abutment members thereby securing said strip from horizontal and vertical movement relatively to said bracket.

5. In a stove, the combination of an up- 50 standing portion, a shelf disposed adjacent the upper end thereof, an upstanding strip on said shelf and brackets secured to said up- 55 standing portion, each having base portions provided with upstanding abutments for embracing the ends and front faces of said strip to secure it against vertical and longitudinal movement relative to said shelf, said base portions also having upstanding abutments spaced inwardly from the first mentioned

abutments for engaging the rear face of the 60 strip at points spaced from its ends.

6. The combination with a stove having an upstanding wall plate and a shelf connected therewith, of a splash plate extending upwardly from said wall and having a horizontally disposed lower flange and a bracket having a base portion secured to said wall provided with a horizontally extending part forming a seat for said flange, said bracket also having upstanding abutments for engaging 65 one end of the splash plate and the front and rear faces thereof to prevent lateral and longitudinal movement of the splash plate.

7. The combination with a stove including an upstanding wall plate having a shelf at 75 the upper edge thereof and a frame for supporting one end of the shelf, of a device for permanently attaching the frame to said wall plate, a splash plate extending upwardly from said wall plate, a bracket having a base 80 portion engaging said wall plate and provided with upstanding abutments disposed in different planes and arranged to engage different portions of the splash plate, and a detachable part on said securing device serving 85 to clamp the bracket upon the wall plate and permitting removal of the same without detachment of any part of the securing device.

8. The combination with a stove including 90 an upstanding wall plate having a shelf at the upper edge thereof and a frame for supporting one end of the shelf, of a screw serving to permanently connect the frame with said wall plate, a splash plate extending up- 95 wardly from said wall plate, a bracket having a base portion engaging said wall plate and provided with upstanding abutments disposed in different planes and arranged to engage different portions of the splash plate, 100 said bracket having an opening through which the screw projects, and a member threaded upon the screw serving to clamp the bracket upon the wall plate, said member and said bracket being removable with the 105 screw in position to connect the frame with the wall plate.

9. In a bracket for supporting a flanged strip on a stove wall, said bracket having a base adapted for attachment to said wall, 110 said base having upstanding abutments in different planes adapted for engagement with different portions of the flanged strip and also having a part with a surface forming a seat for the flange of said strip and extending at substantially a right angle to said abutments.

THOMAS A. SOULTS.
